(57) **CLAIM**

The ornamental design for a pet dental chew, as shown and described.

DESCRIPTION

FIG. 1 is a rear, top and right side perspective view of a pet dental chew according to our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken lines shown in FIG. 3 illustrates a portion of the pet dental treat that forms no part of the claimed design.
